UNITED STATES PATENT OFFICE.

IRVING E. BROWN, OF PROVIDENCE, RHODE ISLAND, ASSIGNOR TO
PROVIDENCE GAS BURNER COMPANY, OF SAME PLACE.

DESIGN FOR AN INSULATING-BLOCK FOR ELECTRIC LAMPS.

SPECIFICATION forming part of Design No. 34,503, dated May 14, 1901.

Application filed April 5, 1901. Serial No. 54,542. Term of patent 14 years.

To all whom it may concern:

Be it known that I, IRVING E. BROWN, a citizen of the United States, residing at Providence, in the county of Providence and State 5 of Rhode Island, have invented and produced a new and original Design for the Insulating-Block of Electric Lamps, of which the following is a specification, reference being had to the accompanying drawings, forming part 10 thereof.

Figure 1 is a side view of the insulating-block, showing my design. Fig. 2 is an edge view of the same. Fig. 3 is a view of the pointed end, and Fig. 4 is a transverse sectional view of the insulating-block.

As shown in the drawings, the leading and material features of the block consist in the dovetail-shaped ribs on each side and the pointed end. The body *a* of the block has on

the two opposite sides the ribs *b b*, extending 20 longitudinally on the sides. The edges of these ribs are undercut to give to them the conventional dovetail shape. The conical-shaped cavities *c c* are formed in the ribs *b b*. One end of the block is beveled on the opposite 25 sides to form the point *d*.

Having thus described my invention, what I claim as new, and desire to secure by Letters Patent, is—

The design for the insulating-block of electric lamps, as herein shown and described.

In testimony whereof I have signed my name to this specification in the presence of two subscribing witnesses.

IRVING E. BROWN.
